Primary Examiner — Karen E Kearney*Assistant Examiner* — Ian Whitmore(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing our new design.

The broken lines illustrate an electronic device with display screen and portions of a graphical user interface, and form no part of the claimed design.
